UNITED STATES PATENT OFFICE.

RALPH BLACK, OF NEW YORK, N. Y.

SPOOL-RACK.

1,377,052.

Specification of Letters Patent.

Patented May 3, 1921.

Application filed April 12, 1920. Serial No. 373,234.

To all whom it may concern:

Be it known that I, RALPH BLACK, a citizen of the United States, and resident of the city of New York, borough of Bronx, in the county and State of New York, have invented a new and Improved Spool-Rack, of which the following is a full, clear, and exact description.

This invention relates to spool racks and has particular relation to an improvement 10 in spool racks designed for use in connection with warping mills or weaving machines.

Devices of this character which are now 15 in general use, are so constructed and of such a limited capacity that when the maximum number of racks are arranged in front of a warping mill or weaving machine, it necessitates the running of the warp threads 20 thereon in sections to obtain the maximum width of cloth, which far exceeds the combined capacity of such a number of racks.

The objections to the accepted forms of 25 spool racks now commonly used, will be obvious from the following concrete example which clearly illustrates the disadvantage of the present system due to the use of the standard forms of spool racks: The maximum capacity of the largest rack now in 30 use, accommodates 336 spools and the width of said racks is such that it is impossible to arrange and operate more than two racks in front of a warping machine; therefore, the maximum number of spools which can 35 now be run under the present system is twice 336 or 672 spools. As the maximum width of cloth woven is approximately 180 inches requiring 5040 warp threads, it necessitates the running of said threads on in eight sections to obtain the required number of 40 threads for the maximum width of cloth.

The principal object therefore, of the present invention is to provide a spool rack which is so constructed and designed as to 45 permit of the combined use of a sufficient number of racks in connection with a warping mill or a weaving machine as to run on the warping mill simultaneously the required number of threads for the maximum 50 width of cloth in one operation.

Another object of the invention is to provide a spool rack which is adjustable in width in order to suit various conditions and render the same capable of use singly or 55 combined with other racks of the same construction for various widths of warping

mills and weaving machines up to and including the maximum.

A further object of the invention is to provide a spool rack which permits of the 60 running of the threads into a weaving machine, or directly onto the warping mill or beam.

A still further object of the invention is to provide a spool rack of the character described which is so constructed as to minimize the space required for a maximum number of spools which are so arranged as to permit of the running of the threads therefrom onto a warping mill, a beam or 70 direct into a weaving machine without the interference of the threads with each other.

Another object of the invention is to provide a spool rack which is capable of folding 75 in order to render the same compact when not in use.

A further object of the invention is to provide a spool rack which is simple in construction, inexpensive to manufacture, strong and durable and which is thoroughly 80 efficient for the purpose for which it is intended.

With these and other objects in view, some of which will be more apparent as the nature, purpose and operation is better understood 85 from the following description and claims, reference is made to the accompanying drawings forming a part of this application and in which—

Figure 1 is a side elevation of a rack constructed in accordance with the invention. 90

Fig. 2 is a plan view thereof.

Fig. 3 is a detail view of the collector bracket removed from the rack.

Fig. 4 is an enlarged fragmentary detailed 95 perspective view of the front standard and the end standards of the side sections of the rack.

Fig. 5 is a fragmentary end view of one of the side sections of the rack illustrating 100 in dotted lines the method of removing or applying a spool to the rack.

Referring to the drawings by characters of reference which denote like parts throughout the several views thereof, 10 and 11 designate identical frame sections or wings each of which includes a rear vertical standard 12, a central vertical standard 13 and a forward vertical standard 14 which may be secured together in spaced relation by any suitable means. The said standards are here illustrated as of rectangular formation in 110

cross section and are each provided with vertically spaced outwardly extending shelves 15, bifurcated at their outer ends, said bifurcations constituting hinge knuckles 16. The 5 said shelves 15 are preferably arranged in horizontal alinement and are designed to support the longitudinal spindle bars 17 which are each formed with a projection 18 constituting a hinge knuckle. The said projection 18 is longitudinally apertured and is adapted to lie between the furcations 16 which are also longitudinally apertured and adapted to aline with the aperture in the extension 18 for the reception of a hinge pin 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 11145 1

- the rack may be effected to vary the distance between the threads leading from the spools, means for retaining said sections in their relatively adjusted positions, and means at 5 the forward end of the rack for guiding the threads from the spools, said means being adjustable in width whereby the width of said means may be made to correspond with the width of the rack.
- 10 3. A spool rack including a pair of frame sections adapted to support a plurality of horizontal rows of spools, said sections having hinged connection at the forward ends to permit of relative separation of the rear 15 ends whereby adjustments in the width of the rack may be effected to vary the distance between the threads leading from the spools, means for retaining said sections in their relatively adjusted positions, means at the forward 20 end of the rack for guiding the threads from the spools, said means being adjustable in width whereby the width of said means may be made to correspond with the width of the rack, and means carried by the forward 25 end of said rack for supporting a collector element for the threads.
4. A spool rack comprising a front standard, a pair of spool carrying frame sections hingedly attached thereto at their forward 30 ends and adapted for relative movements of their rear ends toward and away from each other whereby means is provided for adjustably supporting a plurality of rows of spools to permit of transverse variation

of the distance between the threads leading 35 therefrom, and perforated bars constituting thread guides transversely mounted on the front standard, said bars being transversely adjustable whereby the same may be made to correspond to the width of the rack. 40

5. A spool rack including a front standard and a pair of frame sections adapted to support a plurality of horizontal rows of spools, said sections having hinged connection at one end to permit of relative adjustments of the opposite ends whereby the width of the rack may be varied to effect an adjustment in the transverse distance between the threads leading from the spools, and transversely adjustable bars having 45 perforations therein constituting thread guides carried by the front standard. 50

6. A spool rack including a vertical standard, and a pair of spool supporting frame sections pivoted thereto at one end, said frame sections comprising a plurality of spaced vertical standards, outwardly projecting vertically spaced extensions on said standards, spool supporting bars pivoted respectively to the extensions of each standard 55 for outward swinging movement, a plurality of vertical spindles carried by said bars and adapted to be normally arranged in vertical alignment, means for limiting the outward swinging movement of the bars, and means 60 for retaining said bars in any angular adjustment. 65

RALPH BLACK.
